[57] CLAIM

The ornamental design for an angled shaft for a putter, as shown and described.

DESCRIPTION

FIG. 1 is a perspective view of an angled shaft for a putter showing my new design;

FIG. 2 is a right side elevational view thereof;

FIG. 3 is a top view thereof;

FIG. 4 is a left side elevational view thereof;

FIG. 5 is a bottom view thereof without the club head;

FIG. 6 is a front elevational view thereof;

FIG. 7 is a rear elevational view thereof; and,

FIG. 8 is a bottom view thereof with the club head.

The broken line showing of the club head in FIGS. 1-4 and 6-8 is for illustrative purposes only and forms no part of the claimed design.
